G. S. Tinsley

Inventor.
Lewis Kirk

UNITED STATES PATENT OFFICE.

LEWIS KIRK, OF READING, PENNSYLVANIA.

BRICK-MACHINE.

Specification of Letters Patent No. 26,997, dated January 31, 1860.

To all whom it may concern:

Be it known that I, LEWIS KIRK, of the city of Reading, county of Berks and State of Pennsylvania, have invented certain new and useful Improvements in Brick-Machines; and I do hereby declare that the following is a full and exact description thereof, reference being had to the accompanying drawings, and to the letters of reference 10 marked thereon, making a part of this specification, in which—

Figure 1 is a perspective view, Fig. 2 is a longitudinal elevated section and Figs. 3 and 4 are sectional detailed views thereof.

15 A, forms the base thereof to which the side frames B, B, are secured by means of bolts 1, 1.

C, is a vibrating press lever which is operated by means of the cams E and has 20 its center of motion by means of the bolt 2 which passes through the end thereof and side frames B, B, and is furnished with a lubricating pan D, for lubricating the cams E, and F.

25 G G, are connecting rods attached to the ends of the cross head H, and the vibrating press lever C, by means of bolts 3. The press is elevated by means of spring I which is secured to the base A, by means of screws 30 or bolts.

J, is a cam shaft to which the cams E, and F, are forged solid and has bearings in journal boxes, 4, on side frames B B.

K, is the main driving spur gear wheel 35 secured to one end of shaft J, and meshes into the spur pinion L on shaft M, which also has bearings in journal boxes 5, 5, on side frames B B.

N is a band wheel or pulley secured to 40 shaft M to which the power is applied for operating the machine.

O is a vibrating lever which is operated by the center cam F, and has its center of motion by means of a bolt 6, passing through 45 the end and the side frames B, B.

P is the brick forming plunger which is attached to the vibrating lever O, by means of the link Q and pins 7, 7.

R, is a cam shaft furnished with a cam 50 S, revolving within the cam frame T by which means a reciprocating motion is imparted to the double mold U.

V, V, V, V, are miter gearings secured to

cam shaft J, shaft W and cam shaft R, by which means motion is given to the cam 55 shaft R, which has bearings in journal boxes on side frames B B.

X, X, are brackets or bearings secured to the side frame B, in which shaft W revolves.

Y, Y, are guides secured within side 60 frames B, B in which the cam frame T, slides.

Z is a brace firmly secured within side frames B, B, through which the adjustable 65 clay gage screw a passes.

d, d, are brackets on the frames B, B, upon which the lower end of the discharge plunger c, rests while the press is operating.

t is an adjustable screw in the lower end of plunger c, by which the plunger is raised 70 by lever O, to its proper height.

e, represents the plunger boxes which are firmly secured together by bolts 8, 8, and is secured within the side frames B, B.

f, is a frame secured to the plunger box 75 by means of bolts 8, and may be extended to any desirable length in which the rollers g, g, revolve.

h is an endless apron passing around the 80 rollers by which means the bricks are conveyed from the machine. Motion is imparted to the apron by means of the belt 9, passing around the pulley on the end of roller g, and cam shaft R.

m and n are adjustable gibs and keys by 85 which the reciprocating mold U, may readily be adjusted. The reciprocating mold U, is constructed in parts which are firmly secured together by means of eye bolts s, s, which also forms the joint and connection 90 with the cam frame T, by means of the bolt o.

i is a small square box furnished with a piston j, and works within the mold U and has a projecting flange around the top which 95 when pressed down as represented in Fig. 3, rests upon the top edge of the mold U, and the under surfaces thereof are level with the under surface of the reciprocating mold U. The square box i has depressions at the ends 100 on top which allows it to be pressed up farther than the piston j when both box and piston are pressed against the guards or hooks p, p, by which means the first formation leaves a flange around the top of the 105 brick as represented at y, y.

Figs. 1, 2, and 3, represent the mold U, on the forward stroke, with the flanged brick, y, ready for the second pressing.

Fig. 3, represents the brick as being 5 pressed and the filling box receiving clay.

Fig. 4, represents the mold U, on its back stroke with the pressed brick delivered and a flanged brick again pressed into the mold U.

r is a cap which is firmly secured on the 10 top ends of frames B B.

x and z, form a double hopper by which means two kinds of clay may be used separately at the same time.

v is a flexible gum or leather hose secured 15 to hopper x and filling box w, through which the clay passes from the hopper x and z, into the filling box W. The clay is introduced into the hoppers x and z, and passes down through the flexible hose into the filling box W, and at each forward stroke of the reciprocating mold the clay passes into the back plunger box e, whereon the mold is brought on the back center by the revolving cam S, on shaft R, and the plungers P 20 and c are forced up by means of link Q, bolt t, vibrating lever O, and cam F, by the operation of which the brick is pressed up into the mold U, and is formed with the flange around the top as represented at y, by means 25 of the flanged box i and piston j within mold U, and the guards or hooks P, whence the mold is brought forward by cam S, while the plungers P and c remain up, see Fig. 2, when the center cam F releases lever O and 30 cams E, forces down the cross head H by means of connecting rods G, G, and vibrating press lever, C, upon the flanged box i and piston j of which the under surfaces are

pressed down flush with the under surface of the reciprocating mold U, whereon the 40 brick is perfectly pressed into the front plunger box e by means of the plunger c resting upon the brackets d, d, see Fig. 3, the cams E, at the same time release the vibrating press lever C, by which the cross-head H, is instantly raised by the action of spring I and the mold is again drawn to the back center and the back plunger box is 45 full of clay whereon the vibrating lever O, is pressed up and the pressed brick is delivered 50 out of the machine and another pressed up into the mold as represented at y, Fig. 4, whence the mold comes forward and slides the pressed brick off of the end of the delivering plunger c onto the traveling apron h 55 by which means the brick may be conveyed to any desirable distance, the adjustable screw in brace Z can be readily adjusted while the machine is in operation to suit different quantities and qualities of clay. 60

What I claim as my invention and desire to secure by Letters Patent is—

1. The double hoppers x and z in combination with the flexible hose v, when constructed and arranged as and for the purpose set forth. 65

2. I also claim the flanged box i and piston j in combination with the reciprocating mold U, and crosshead H when constructed, arranged and operated as herein described, 70 and for the purpose set forth.

LEWIS KIRK.
